Kevin Prince(57) **CLAIM**

I claim the ornamental design for a snuffer tool, as shown and described.

DESCRIPTION

FIG. 1 is a perspective view of a snuffer tool, showing my new design;

FIG. 2 is a front elevational view thereof, the rear elevational view being a mirror image thereof;

FIG. 3 is a left-side elevational view thereof, the right-side elevational view being a mirror image thereof;

FIG. 4 is a top plan view thereof;

FIG. 5 is a bottom plan view thereof; and,

FIG. 6 is a cross-sectional view of FIG. 4, taken along lines 6-6.

The broken lines in FIGS. 1, 2 and 6 depict portions of the snuffer tool that form no part of the claimed design.
